Attorney

UNITED STATES PATENT OFFICE.

MICHAEL H. SHANLEY, OF GRANBURY, TEXAS.

VENTILATOR.

SPECIFICATION forming part of Letters Patent No. 340,829, dated April 27, 1886.

Application filed February 25, 1886. Serial No. 193,163. (No model.)

To all whom it may concern:

Be it known that I, MICHAEL H. SHANLEY, a citizen of the United States of America, residing at Granbury, in the county of Hood 5 and State of Texas, have invented certain new and useful Improvements in Ventilators; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 My invention relates to certain new and useful improvements in combined flues and ventilators; and it consists in the construction and combination of the parts, as will be hereinafter fully set forth, and specifically pointed 20 out in the claims.

In the accompanying drawings, which illustrate my invention, Figure 1 is a side view of a combined flue and ventilator constructed in accordance with my invention. Fig. 2 is a 25 vertical section. Fig. 3 is a transverse section taken through the line α α of Fig. 2. Fig. 4 is a detail perspective view.

My improved flue and ventilator is applied to the roof of a building, and extends through 30 the same to the apartment which it is desired to ventilate, so that the same can be employed during the winter months as a smoke-exit passage and during the summer as a ventilator-passage compartment.

35 A refers to the outer casing, which extends through the roof and above the same, and downward into the compartment. This outer casing is provided centrally with a flue, B, which extends from the compartment or room, 40 preferably near the ceiling, to a suitable distance above the roof, and a transverse cover-plate, b, is secured to the outer casing, A, and through a central opening therein the central flue, B, passes. Above the plate B, to the casing A, is attached a suitable cap, C, of ornamental configuration, which is provided, near its upper part, with a cover portion, C', between which and the lower portion, C, is a space, through which impure air from the apartment 45 may pass in summer or smoke in winter. The lower portion of the cap C has near its base a series of perforations, e, through which air

may pass, so as to create an upward draft above the flue through the exit-opening beneath the cover-plate C'. 55

The space D, between the central flue, B, and the outer wall or casing, may, if desirable, be formed in two independent compartments, or may consist of a single compartment, as desired. 60

The outer casing, A, near its upper end, is provided on its four sides with shields or screens d, and beneath the same are located openings E, said screens or curved plates d being located above said openings, so as to 65 prevent rain or snow entering therein. Beneath the openings E the outer casing, A, is provided with hinges e, one of the leaves of said hinges being secured thereto, while the opposite leaf is attached to the under side of 70 the funnels F, said funnels being fully illustrated in Fig. 4 of the accompanying drawings. The funnels have attached near their inner ends staples f, to which flexible connections are secured, said flexible connections 75 extending therefrom downwardly through the compartment D and into the chamber, the lower ends being provided with rings or knobs.

If desirable, the compartment D may have located therein tubes G, through which the 80 flexible connections or cords g will pass, these tubes also serving as conduits for the air from the interior of the building, and these tubes, when desired, may extend under the outer compartment, A, to suitable points within the 85 room. When the tubes G are not employed, the outer casing, A, has perforations, through which the air may pass.

When it is desired to ventilate a compartment, the operation of my invention is as follows: The stove-pipe from the heating apparatus is connected to the central tube, B, which forms the smoke-exit passage, and when it is desired to have air in the room for ventilating purposes the funnel on the side from which 95 the wind is blowing is raised and held in an elevated position by drawing upon and securing the flexible connection g, which causes the air to enter the tube through which the flexible connection passes into the room. The funnels are of sufficient weight to drop automatically, and are raised and held in a raised position by the flexible connections hereinbefore described. 100

By the construction hereinbefore described I provide an air-space between the air-inlet pipe, the outer casing, and the central flue. The central flue is removable, so that when the same is burned out it can be readily replaced.

I claim—

1. The improved combined flue and ventilator herein described, consisting of an outer casing, A, surmounted by a cap and provided with a central flue, funnels F, hinged to the outer casing and provided with flexible connections for elevating the same, and means for conducting the air downward from said funnels, substantially as shown, and for the purpose set forth.

2. In a combined flue and ventilator, an outer casing, A, having screens or shields d attached thereto, openings located under said

shields, and hinged funnels adapted to be elevated from within the building, and a central flue through the outer casing, the parts being organized substantially as shown, and for the purpose set forth.

3. In a combined flue and ventilator, an outer casing provided with a central flue and tube, G, located between said flue and casing, and funnels F, hinged to the outer portion of the casing, so as to lead into the tube G, and means for elevating said funnel from the interior of the building, substantially as shown, and for the purpose set forth.

In testimony whereof I affix my signature in presence of two witnesses.

MICHAEL H. SHANLEY.
